No. 732,596.

PATENTED JUNE 30, 1903.

C. A. SPORRONG.

APPARATUS FOR TEACHING GUN PRACTICE.

APPLICATION FILED JULY 29, 1902.

NO MODEL.

FIG. 1.

UNITED STATES PATENT OFFICE.

CARL ANTON SPORRONG, OF STOCKHOLM, SWEDEN.

APPARATUS FOR TEACHING GUN PRACTICE.

SPECIFICATION forming part of Letters Patent No. 732,596, dated June 30, 1903.

Application filed July 29, 1902. Serial No. 117,527. (No model.)

To all whom it may concern:

Be it known that I, CARL ANTON SPORRONG, a subject of the King of Sweden and Norway, and a resident of Stockholm, Sweden, have **5** invented certain new and useful Improvements in Apparatus for Teaching Gun Practice, of which the following is a specification.

My invention consists of further improvements **10** in apparatus for teaching gun practice of the character described in my Patent No. 707,729, dated August 26, 1902.

The object of my invention is to provide improved means whereby the practical operations **15** of target-shooting may, so far as the drill exercise is concerned, be carried on without the waste of ammunition and the dangers incident thereto and also without the long range necessary to the common practice.

20 The invention comprises, essentially, a universally-jointed gun-support, which gun may be a dummy or false gun and is subject while on said support to the manipulations of the practitioner, said support allowing practically the same deviations of the gun when being sighted as in the common practice, with means for transmitting the deviations to a pointer so connected to the gun-support as to keep in such alignment relatively to the line **25** of the gun-sight as to point to the same object, and a clamping device which is automatically actuated simultaneously with and is set in operation by the pulling of the trigger and instantly locks all the parts fast in **30** the positions they occupy against movements in any direction at the instant the trigger is pulled, so that the pointer shows with relation to a fixed center representing the bull's-eye of the target the deviations due to the **35** practice of the unskilled operator as they are shown on the ordinary target, as hereinafter described, reference being made to the accompanying drawings, in which—

Figure 1 is a vertical section of the apparatus **45** without the gun, the section being taken in a plane at right angles to the vertical plane of the gun. Fig. 2 is a vertical section of the apparatus in the plane of the gun and side view of the gun mounted thereon with a part **50** of the gun broken out. Fig. 3 is mainly a horizontal section of the apparatus in the plane of the universal axes of vibration of the

gun-support. Fig. 4 is a horizontal section showing a modification of the clamp. Fig. 5 is a detail showing the clamp setting and **55** tripping lever. Fig. 6 is a detail showing the trigger fixed on the gun-support, as it may be when a dummy gun is used.

A represents the gun, and a represents a support of trough-like construction in which **60** the gun may be placed, so as to be gripped together with the gun by the left hand, as the ordinary gun is gripped when placed against the shoulder for use, while the right hand grips the part *l* only of the stock of the gun. **65** The gun is temporarily secured in the support *a* by a couple of tap-screws *a*², for which suitable holes have to be tapped in the under side of the gun. The support *a* is at its rear end mounted on the top of a vertical **70** pivot-standard *b*, which at about the middle of its length has a support in a clamp *c*, through which it is fitted so as to rotate, said clamp being carried by trunnion-pivots *d* in housings *e*, set upright on a base-plate *r*, so **75** that the support may shift in a vertical plane for adjustment as to elevation of the trajectory, while rotation of standard *b* horizontally accommodates the lateral range. The clamp *c* carries a step-bearing *f* for the pivot *g* of **80** the lower end of the standard *b*, said bearing being suspended a suitable distance below by hangers *h*. The gun is thus mounted so as to work universally in the hands of the operator practically the same as a gun wholly **85** supported in the hands, and with the gun so mounted a pointer *i*, located below and preferably to the left hand of the gun and universally pivot-jointed at *j*, is coupled to the standard *b*, so that the pointer automatically **90** follows the line of the gun-sight in all the deviations it may make when manipulated by the operator, and when the gun is accurately pointed with relation to the object aimed at the said pointer registers with a bull's-eye **95** mark *k*, fixedly set on a transparent support *m* directly in front of the pointer, and thus shows that aim was correct, and whatever deviation there may be of the pointer relatively to this mark represents the measure of the **100** inaccuracy of the operator. The connection of the pointer-staff *i* with the standard *b* is preferably by means of a metallic strip or wire spring *l*, having several coils *13* and a

rigid arm 14 interposed between said spring and the staff for an elastic connection; but this may be modified at will. The universal fulcrum-joint pivot of the pointer-staff *i* may 5 be constructed in any approved way. It is to be understood that the pointer is not necessarily located below nor to one side of the vertical plane of the gun. In regard to these particulars the arrangements specified are 10 only such as preferred. To fixedly set the pointer exactly in the position occupied at the instant of pulling the trigger and retain it a short time for observation, the trigger *n* is made to release an automatic clamp, which at 15 once rigidly arrests all movements of the gun-supporting apparatus, and thus rigidly sets the pointer in whatever relation it may be to the bull's-eye mark. The clamp, which is of a duplex character, may be constructed in 20 various ways, and I do not limit myself to any particular construction. The construction which I represent herein as one example of such devices suitable for carrying out my invention consists of the housings *e*, between 25 which two clamp-jaws *c* are pivoted, said housings being made slightly elastic in their supporting parts *e'*, and the flange *p* of the internally-screw-threaded sleeve *q*, placed outside of one of the housings and coupled together 30 by bolts *s*, extending through slots *t* of the clamp-jaws *c*, allowing said clamp-jaws limited rotatory movement on their axes without hindrance by said bolts, said housings being also free for slight movement along the bolts, 35 or at least the one between the flange *p* and the block *c* must be so. In the sleeve *q* is a clamp-operating screw *u*, to one end of which, projecting from the outer end of the sleeve, a hand-lever *v* is attached, while the 40 inner end of said screw has when screwed up contact with the housing *e*, against which the flange *p* of the sleeve *q* bears. The lever *v* carries a ratchet-segment *w* on the extremity of its short arm, which engages with a 45 pawl *x* when the lever is turned by hand to the left or in the direction to retract the screw and holds it for maintaining the relaxed condition of the clamp. On the sleeve *q* between flange *p* and a collar *y* is a coiled spring *z*, one 50 end of which is secured to flange *p* at 2 and the other end engages the short arm of lever *v* at 3, said spring being so adjusted that under tension it thrusts the lever so as to tighten the clamp when ratchet *w* is released 55 from the retaining pawl-bit *x*. This pawl-bit is carried on a lever 4, pivoted at 5 and having a spring 6 normally keeping the said bit in engagement with the ratchet *w*. The lever 4 reaches into a recess 7 in the standard *b* just 60 above the step-bearing of said standard, so that a rod 8, set upright in the hollow axis of the standard, may rest at its lower end on or slightly above the lever 4 near its free end. This rod extends upward to the top of the 65 standard *b*, or thereabout, where the arm 9 of the trigger *n* rests on it above a perforation 10 made through the trigger-guard plate for

the rod, so that when the trigger is pulled lever 4 is depressed, which releases pawl-bit *x* from the ratchet *w*, allowing spring *z* to act 70 and tighten the clamp at the instant the trigger is pulled, and thus fixedly set the pointer in the relation to the bull's-eye *k* that the gun-sight bears to the object aimed at, which may be any object at a suitable distance or a common target, if desired. The jaws *c* clamp the standard *b* and fix the pointer relatively to horizontal range, and the housings clamp the jaws *c* and fix the pointer relatively to vertical range. The lever 4 carries a plate 21, the 80 breadth of which is coextensive with the lateral range of the end of the rod 8 due to the oscillations of the clamp *c* on its trunnions, and thus insures uninterrupted connection of the two notwithstanding the oscillations. 85 The spring 6 and lever 4 return the rod 8 to bearing contact with the trigger-arm 9. The lever *v* is pulled forward again and is automatically again engaged by the pawl-bit *x* for releasing the clamp preparatory to the next 90 operation.

The base-plate *r* is detachably and adjustably clamped to an arm 14, which is similarly clamped to a post 15, that may have any suitable support.

A protective inclosing case 16 is applied to the apparatus below the support *a*, and a funnel-shaped protector 17 for the pointer *i* is suitably attached to a post 11 of said base and carries at its larger end the before-mentioned 100 transparent support *m*, through which the pointer *i*, indicating the results of the efforts of the practitioners, is seen, the range of said funnel being such that the operator has the mark *k* and the pointer in his visual range after 105 firing the gun, thus enabling him to observe the result of his efforts without removing from the position he occupies when manipulating the gun.

As one modification of the clamp, a solid 110 block *c'* is represented in lieu of the jaws *c* in Fig. 4 with a thrust-pin *c'* fitted in suitable perforations of the housings *e* and the side of said block intermediate of support *a* and the screw *u* to thrust against the side of support *a* directly for clamping said support against rotation. Thus the clamp is not limited to such jaws *c*. When the jaws *c* are used for clamping the support *a* against rotation, the hangers *h*, by which the step-bearing *f* is suspended from said jaws, are divided in the upper part, as shown at *h'*, Figs. 2 and 3, to allow them to spring sufficiently for clamping said support.

In Fig. 6 the support *a*³ is more particularly 125 adapted for a dummy gun, and the trigger *n'* is mounted on said support, as it may be, if preferred.

What I claim as my invention is—

1. The combination of the universally-movable gun-support adapted for the application of a gun in connection with it as in sighting the gun and shooting, a gun mounted thereon, a pointer having a universally-

jointed support and connected with the gun-support so as to maintain parallelism with the deviating line of the gun-support, a bull's-eye mark located in the line which the pointer occupies when the gun is truly sighted with relation to the object aimed at, an automatic clamp to lock the gun-support when the trigger is pulled and secure the gun and pointer against movement in any direction, setting devices for holding the clamp in readiness for action, and tripping mechanism for said holding devices actuated by the trigger.

2. The combination of the gun-support adapted for the application of a gun for use in connection with it as in sighting the gun and shooting, a gun mounted thereon, the universally-jointed mounting of said support, a pointer having a universally-jointed support, and connected with the gun-support so

as to maintain parallelism with the deviating line of the gun-sight, a bull's-eye mark located in the line which the pointer occupies when the gun is truly sighted with relation to the object aimed at, the range of said pointer and mark being such that the operator has them in his visual range when in the position for operating the gun, an automatic clamp to lock the parts in the positions occupied when the trigger is pulled, setting devices for holding the clamp in readiness for action, and tripping mechanism for said holding devices actuated by the gun-trigger.

Signed at Stockholm this 11th day of July, 1902.

CARL ANTON SPORRONG.
